DESIGN FOR A SOAP DISPENSER OR THE LIKE

Walter S. Finnell, Elkhart, Ind., assignor to Finnell System, Inc., a corporation of Indiana

Application June 6, 1939, Serial No. 85,372

Term of patent 7 years

To all whom it may concern:

Be it known that I, Walter S. Finnell, a citizen of the United States and resident of Elkhart, in the county of Elkhart and State of Indiana, have invented a new, original, and ornamental Design for a Soap Dispenser or the like, of which the following is a specification, reference being had to the accompanying drawing, forming part thereof, in which Figure 1 is a front elevation of the new soap dispenser; Figure 2 is a left side elevation of the soap dispenser; Figure 3 is a right side elevation of the soap dispenser; and Figure 4 shows the soap dispenser as viewed from the top.

I claim:

The ornamental design for a soap dispenser or the like, substantially as shown.

WALTER S. FINNELL.
